UNITED STATES PATENT OFFICE

ARTHUR H. SWETT, OF CHICAGO, ILLINOIS

TAG STRUCTURE

Application filed July 2, 1930. Serial No. 465,294.

My invention relates generally to tag structures, and has to do particularly with eyelet or tubular rivet means for non-detachably securing tags of the fold-over tongue, etc., types to the articles which they are to identify.

As is well known, it is quite desirable, for the protection of a merchant, to apply to merchandise, such as articles of clothing, etc., an identification tag which cannot be detached without distortion and without showing evidence of having been detached or tampered with. This safe-guarding arrangement tends to prevent the customer from securing merchandise on approval, using the same and then returning it to the merchant. This practice is quite desirable in connection with all kinds of merchandise which is handled from time to time, preventing loss of identification, cost, size, etc., marking; and it also avoids the changing of any of these cost, identifications, etc., markings from one article to another, except by authorized persons. It is a protection to the merchant from every standpoint, even during shipping of goods from one place to another.

While this practice has been adopted in several instances, the means for accomplishing the desired results have been of such character as to entail considerable inconvenience, particularly in securely fastening the component parts of the tag. For example, in certain instances, separate rivets or eyelets have been employed to secure folded sections of the tags together, requiring separate handling of the tags and rivets or eyelets. This not only requires special skill for proper attachment, but the separate eyelets and rivets are quite small and are difficult to handle and properly position on the tag to avoid covering up identification marks and the like. This makes the work of securing the tag sections quite tedious and tends, naturally, toward carelessness whereby the full advantages sought are not obtained.

One of the objects of my invention is to provide tag structure adapted to the foregoing uses which eliminates the shortcomings of prior structures, and to that end my invention contemplates the use of novel eyelet

or tubular rivet means permanently secured to the tag in its manufacture, thereby eliminating separate handling of the eyelet or rivet by the merchant, his clerk, or other user.

Another object is to provide novel rivet structure which includes a tubular barrel part having at one end a laterally-extending base part of substantial size, which base part is adapted to engage one side of the tag material; and the tubular barrel part is so formed that a part of the material forming the same is struck outwardly therefrom and adapted to be clinched down upon the side of the tag material opposite the rivet base to securely clamp the tag material between such struck-out part and the base. Such struck-out portion is so formed that an upstanding tubular part remains to be engaged with and clinched upon another part of the tag.

A further object is to provide a strong and durable rivet structure attached to the tag in such a way that it cannot be loosened and removed without so distorting the rivet and tag as to prevent further use of the same, the entire structure being of such character that any tampering and distortion of the same will be readily detected. The rivet structure is of sufficient rigidity and strength, and it is so shaped and attached, so that the tag must be practically torn apart in order to detach the rivet and tag sections.

Further objects are to provide tag structure including tubular rivet means for joining sections of the tag structure together, which rivet means is permanently attached to a section of the tag with metal reinforcement on both sides of the tag material around the opening in such material through which the rivet projects thereby strengthening the tag material at that point and tending to prevent tearing out of the same except under abnormal conditions; and to provide, more specifically, the tubular barrel portion with tangs cut therefrom and adapted to be pressed outwardly and downwardly to securely grip the tag material to permanently attach the rivet to the tag, or to strike from the tubular wall an annular horizontal flange for securely holding the rivet to the tag,—the arrange-

ment in both cases being such that, when the remaining upstanding tubular part is engaged with another portion of the tag and crimped, the turned-down tangs or flange is concealed and rendered inaccessible avoiding tampering in an attempt to detach the tag structure.

Other objects and advantages will become apparent as this description progresses and by reference to the drawings, wherein,

10 Fig. 1 is a plan view of one form of tag structure which I have chosen to illustrate my invention, the tag being shown in its open and unfolded or unattached condition;

15 Fig. 2 is a view showing the tag of Fig. 1 with its sections folded and permanently secured together;

20 Fig. 3 is a sectional view taken substantially on line 3—3 of Fig. 1;

25 Fig. 4 is a sectional view taken substantially on line 4—4 of Fig. 2;

30 Fig. 5 is another view of the tag structure shown in Fig. 1, but illustrating the tubular rivet mounted in a different location than shown in the tag structure of Fig. 1;

35 Fig. 6 is a view of the tag structure of Fig. 5, showing the tag sections folded and attached;

40 Fig. 7 is a section taken substantially on line 7—7 of Fig. 5;

45 Fig. 8 is a section taken substantially on line 8—8 of Fig. 6;

50 Fig. 9 is an enlarged vertical sectional view through the rivet structure shown in Figs. 1, 3, 5 and 7, and taken substantially on line 9—9 of Fig. 1;

55 Fig. 10 is an enlarged sectional view taken substantially on line 10—10 of Fig. 2;

60 Fig. 11 is a plan view of the structure shown in Fig. 9;

65 Fig. 12 is a vertical sectional view, similar to Fig. 9, but showing another form of rivet structure embodying my invention; and

70 Fig. 13 is a top plan view of the structure shown in Fig. 12.

75 Referring particularly to the form shown in Figs. 1 to 4, inclusive, the tag takes the form of a blank having a rectangularly-shaped body portion 20 with a narrow rectangularly-shaped tongue 21 projecting from one end thereof. The tag body may be creased as at 22 providing foldable sections 20^a and 20^b, and the tongue 21 may be likewise creased for folding as at 23, whereby the entire tag structure may be folded in the manner, and to the shape, illustrated in Figs. 2 and 4.

80 This tag structure is of a character which 85 may be readily and permanently secured to numerous articles and is completely adapted for that purpose when it leaves the place of manufacture. More particularly, I employ a tubular rivet 24 permanently secured in an opening 28 formed in the tag body section

20^b. This rivet (Figs. 9—11) is provided with a tubular barrel part 25 having at one end a laterally extending flange 26 constituting a base part of substantial width. This upstanding, tubular part has tangs 27 struck 70 from its vertical wall at, preferably, diametrically opposed points; and while I, preferably, employ two such tangs in this form, the number of the same may be varied, if desired, without departing from my invention. 75 With this structure, the rivet may be permanently secured to the tag so that when the same is delivered to the user, the rivet structure will constitute a part of the tag, eliminating the necessity, and inconvenience, of 80 handling separate rivets, etc. as hereinabove more particularly mentioned.

Any desired, and suitable, form of tool may be employed for the cutting out of the tangs 27. These tangs may, preferably, be cut out 85 before the rivet is inserted in the tag opening 28 or the tubular rivet with uncut side walls may be first inserted in the tag opening and a proper tool then used which cuts and crimps and clamps the tangs in place as illustrated 90 and described. In securing the rivet to the tag, its barrel portion 25 is passed through the opening 28, whereupon the tangs are forced outwardly and downwardly upon the surface of the tag material as best illustrated 95 in Figs. 9 and 10. The tangs are pressed firmly down and permanently act and, during this action, the base portion 26 serves as a die-like support for effecting the proper clinching or crimping of the tangs 27. In 100 this manner, the tag material is tightly gripped between the tangs 27 and base 26 and the tag material around the opening 28 is reinforced making it practically impossible to detach the rivet from the tag without so distorting both the rivet and the tag as to render the same of no further use. This metal reinforcement-attachment strengthens the tag structure as a whole, making the same 105 more nearly foolproof and tamperproof in its article-attached condition as is quite desirable.

After the rivet has been fixed in place, the tag structure is ready for use by the merchant, or other user, who carries the same 110 in stock in the condition illustrated, say in Fig. 1, until he is ready to attach it to the article to be identified. When the user attaches the tag, the tag tongue 21 is looped 115 engaged with some suitable part of the article in such a way that its free end may be turned back to bring one of the openings 29, 29^a and 29^b into coincidence with the upstanding, tubular portion 25 of the rivet, which tubular portion is then passed through the aligned opening. The tag section 20^a is next folded 120 over to the position shown in Figs. 2 and 4 so that the tubular portion 25 of the rivet may be projected through the opening 30. When the parts are thus engaged, a suitable clinch-

ing or crimping tool, of any well known form, may be applied to the rivet structure to clinch the outer projecting tubular portion thereof to the position or condition indicated at 25' in Figs. 2, 4 and 10. Thus, the tag sections 20^a, 20^b and the tongue are all securely interlocked, and the walls of the rivet which have been clinched are sufficiently rigid to prevent unclinching of the same for removal of these parts. The parts are so firmly secured together that they cannot be separated without either tearing the tag or so distorting the same or the rivet that such tampering may readily be detected and the merchant or user, consequently protected, as intended.

It will be noted that with this arrangement, the rivet structure is of tubular form having at least three lateral projecting portions (when finally clinched) which are in substantially vertical alignment with each other and so related as to firmly hold the several fastened sections of the tag, to support all of the openings through which the rivet passes to more positively prevent unauthorized detachment. In the crimping of the outer portion of the tubular barrel part 25', the base portion 26 and down-turned or clinched tangs 27 provide additional die-like supporting surfaces for the clinching action, insuring the proper uniform and rigid crimp action which is quite essential for best securement of the tag sections. Further, with this arrangement, the uniform association of the crimped tubular barrel part 25' and the base part 26 with the tag sections provides structure which will withstand greater pull action as against these parts without tearing than has heretofore been achieved with prior structures.

In Figs. 5 to 8, inclusive, I have shown a tag shaped similarly to that of Fig. 1 but, in this case, the rivet 25^a is fixedly mounted in an opening 31 at the free end of the tag tongue 21^a. In folding this tag structure, the two tag body sections 20^c and 20^d may be folded upon each other, the tag tongue 21^a then folded so that its tubular rivet portion will project downwardly through openings 32 and 33, for clinching of the rivet as illustrated in Figs. 6 and 8, and, as previously described in connection with the form of Figs. 1 to 4, inclusive.

In both of the foregoing structures, the tag body sections may contain various identification marks, with respect to size, style, cost, etc., on both sides thereof. Some of this information, when the tag is folded may be readily observable while other such information may be concealed, and protected, by the folding and securing of the sections.

In Figs. 12 and 13, I have shown another form of rivet embodying my invention. This form, like that of Figs. 9, 10 and 11, is provided with a tubular barrel part 34 and an annular base part 35 extending laterally from the lower edge thereof. To secure this rivet

in place, it is inserted through the opening 36 in the tag material 37 and a tool of suitable form is then employed to crimp the tubular side wall at an intermediate point, or to double it on itself in such a way as to form a laterally projecting annular flange 38 which, when fully formed, engages the side of the tag material opposite the rivet base 35. This provides on both sides of the tag material around the opening 36, an annular gripping flange or ring which greatly strengthens the structure as a whole as hereinbefore more particularly mentioned in connection with the form of Figs. 9, 10 and 11. In the mounting of this form of rivet, the base portion 35 also serves as a die-support for the forming of the annular holding ring 38.

While I have referred to two adaptations of my invention, and have described two different forms of rivet structure embodying the same, it will be understood that other changes in details and arrangement of parts may be made without departing from the spirit and scope of my invention as defined by the claims which follow. For example, instead of folding the sections of the tag body, the tongue part only, or only one section of the tag, may be folded over and attached. In that case, the rivet attachment, etc. would be the same as above described.

I claim:

1. Tag structure comprising a body portion including a plurality of integral sections defined by a crease line and adapted to be folded about said crease line upon each other and retained in that condition, said sections having openings therein positioned to align in said folded position of said sections, and means coacting with the walls of said openings for retaining the tag in folded condition comprising a tubular rivet having a flat base with an upstanding tubular portion secured in the opening of one of said sections by a part of the material of the wall of said tubular portion being forced laterally therefrom and clamped down upon the tag material around the walls of the opening in which said rivet is mounted, for permanently securing said rivet to the tag.

2. Tag structure comprising a foldable body portion having apertures therein adapted to align in the folded position of the body, and means coacting with the walls of said apertures for retaining the tag in folded condition comprising a tubular rivet having a flat base, an upstanding tubular portion permanently secured in one of said openings, a rivet-securing element in the form of an integral part of the material of the wall of said tubular portion, said element being clamped or crimped down upon the tag material around said rivet for permanently securing said rivet to the tag, and said element being so related to said rivet base and the tag material around said rivet as to reinforce said

latter material, with said upstanding tubular portion being adapted to be passed through another of said openings when said body is folded, said tubular portion being deformable for securing of the tag body in its folded condition.

3. Tag structure comprising a foldable body having openings adapted to align in the folded condition of said body, a tubular rivet initially and permanently secured in one of said openings, which rivet comprises a comparatively wide base part adapted to engage one side of the tag material around the opening in which said rivet is secured, and 15 an upstanding tubular part projecting through said opening, tangs cut from the material of said tubular part and crimped down upon the tag material around said opening directly above said base leaving an upstanding tubular part adapted to be received in 20 the other of said openings and to be deformed by clinching or otherwise to secure said body and sections together permanently.

4. Tag structure comprising a foldable body having openings adapted to align in the folded condition of said body, a tubular rivet initially and permanently secured in one of said openings, which rivet comprises a comparatively wide base part adapted to engage 25 one side of the tag material around the opening in which said rivet is permanently secured, and an upstanding tubular part projecting through said opening, a laterally-extending flange carried by said tubular part 30 and formed by laterally expanding the wall of said tubular part, said flange being so formed and forced downwardly upon the tag material around said opening as to permanently fasten the rivet to said body and to 35 firmly reinforce the wall of the opening in which said rivet is permanently secured directly above said base, said flange being so formed as to leave said upstanding tubular part in condition to be secured in the other of 40 said openings and to be deformed by clinching or otherwise to secure said body in its 45 folded condition.

5. Tag structure comprising a foldable body, an integral flap extension adapted to 50 be folded toward and upon a folded portion of said body, said body having openings adapted to align in the folded condition of the body and said extension having an opening adapted to align with said body openings 55 when said extension is folded upon said body, and means coacting with the walls of said openings for retaining the tag in folded condition comprising rivet structure adapted to be secured in one of said openings to constitute 60 a permanent non-detachable part of the tag, said rivet structure having a laterally extended, substantially flat, annular base part, a tubular part upstanding therefrom adapted to be passed through said one opening 65 with said base resting firmly against the

tag material around said one opening, the rivet being secured in said one opening by a part of the metal of said tubular part struck laterally therefrom and crimped downwardly 70 upon the tag material around said one opening and directly above said base, leaving an upstanding tubular rivet part adapted to be inserted in the others of said openings and to be deformed by crimping, or otherwise, at its outer end down upon the tag material around 75 another of said openings so as to secure said body and extension together with superimposed, aligned metal reinforcement around all said openings to increase the strength and durability of the tag structure as a whole. 80

6. In a tag structure, a foldable body having openings adapted to align in the folded condition of the body, said body having an integral foldable extension provided with an opening adapted to align with said aligned 85 body openings in the folded condition of both said body and said extension, and a rivet including means permanently securing said rivet in one of said openings and a part projecting beyond said means and adapted to 90 pass through the others of said openings and be deformed in the folded condition of said body and its extension for permanently securing the folded portions in folded condition.

7. In a tag structure, a foldable body having openings adapted to align in the folded condition of the body, and a rivet including means permanently securing said rivet in one of said openings and a part projecting beyond 95 said means and adapted to pass through the 100 other of said openings and be deformed in the folded condition of said body for permanently securing the folded portions in folded condition.

In testimony whereof, I have subscribed 105 my name.

ARTHUR H. SWETT.
